UNITED STATES PATENT OFFICE.

ELGIE C. AULD, OF SCOTTDALE, PENNSYLVANIA.

FLUME.

1,230,980.

Specification of Letters Patent. Patented June 26, 1917.

Application filed February 14, 1916. Serial No. 78,135.

To all whom it may concern:

Be it known that I, ELGIE C. AULD, a citizen of the United States, residing at Scottdale, in the county of Westmoreland and State of Pennsylvania, have invented certain new and useful Improvements in Flumes, of which the following is a specification.

My invention relates to the construction of flumes used in conducting water or similar liquids from a place of supply to a place of further treatment or use. While not limited to such use the invention more particularly relates to the construction of flumes for use in conveying and aerating or otherwise treating acid mine water.

One object of the invention is to provide a flume of novel construction having improved means whereby water or other fluid is automatically agitated and aerated and in some cases oxidized during the flow of the fluid therethrough.

A further object of my invention is the provision of a flume having the novel features of construction and combinations of parts shown in the drawings and covered by the appended claims and to be more fully described hereinafter.

Referring now to the drawings forming part of the specification, Figure 1 is a longitudinal sectional side elevation showing a flume constructed and arranged in accordance with my invention.

Fig. 2 is a sectional end elevation on a larger scale, the section being taken on the line II—II of Fig. 1, showing a double compartment flume as constructed and arranged in accordance with my invention.

Fig. 3 is a detail plan on an enlarged scale with part of the cover removed showing details in the construction of the flume of Figs. 1 and 2.

Fig. 4 is a longitudinal sectional side elevation of the portion of the flume shown in Fig. 3.

Fig. 5 is a top plan of one section of the removable cover forming part of the flume shown in the preceding figures.

The flume illustrated is provided with a vertical partition by which it is separated lengthwise into two separate and independent compartments, and is constructed of wood, although concrete or other suitable building material or combination of ma-

terials may be used when found necessary or desirable.

In the accompanying drawings the numeral 2 designates the bottom, and 3 and 4 the side walls of the flume. In the construction shown a vertical partition 5 is provided which extends from end to end of and divides the flume into two separate and independent compartments 6 and 7.

Positioned on top of the flume is a cover which is made in sections 2^a so as to be removable to enable any particular section to be removed without disturbance of the remaining sections and thereby permit of inspection of or repairs to the interior of the flume at any point in the length thereof.

Secured within each compartment 6 and 7 at suitable short intervals in the length thereof, is a series of bottom baffles 8 which extend transversely between the opposite faces of the side wall 3 or 4 and the central partition 5. These bottom baffles extend upwardly with the upper edge 9 thereof terminating below the top of the flume and a series of openings 10, which as shown are triangular in outline, are provided in the lower edge of the bottom baffles to permit of any sludge or finely divided solids being carried from one side to the other of the baffles 8 and eventually to reach the discharge end 11 of the flume, the bottom of the flume forming the base or bottom side of the triangular openings.

Between each of the adjoining bottom baffles 8 is a depending baffle or partition 12 which extends vertically from the top of the flume to a point some distance above the bottom 2. The lower edge 13 of the series of upper baffles terminates short of the bottom 2, and as shown, the lower edges 13 of the depending baffles or partitions are in a plane below the plane of the upper edges 9 of the series of bottom baffles 8.

The depending baffles 12 near the upper edge thereof, is provided with a series of recesses or openings 14, rectangular in outline as shown, to permit of air passing from one side to the other of the depending baffles without passing beneath these baffles, the air flowing in the direction in which the water is carried or from the entrance end 19 toward the discharge end 11 of the flume.

A series of openings 15 is provided in each of the sections 2^a of the top or cover, the

row of openings 15 in each section of the top being located closely adjacent to one of the depending baffles or partitions 12 on the discharge side thereof, the purpose of the 5 openings 15 being to admit air, the flow of which is induced by the flow of water or other fluid through the flume.

The entrance end 19 and also the discharge end 11 of the flume is open so as to 10 permit of the free entrance and discharge of the water or fluid conveyed therethrough.

Battens 16 are provided on the sections 15 of the cover or top, and battens 17 and 18 also are provided on the bottom and sides of the flume at suitable intervals in the length thereof.

In the use of my improved flume it will 20 be located so as to extend lengthwise with its entrance end 19 in position to receive the water or other fluid from the source of supply, and with its discharge end 11 in position to deliver the treated water or other fluid into the proper tank or receptacle.

When a stream of neutralized mine water 25 or other fluid being treated is delivered into the receiving end of the flume it will flow therethrough, the bottom 2 being inclined at a sufficient angle to the horizontal to cause the rapid flow of fluid through the compartments.

The stream of water or other fluid in flowing 30 through the flume engages with and is backed up by and flows over the first of the series of bottom baffles 6 and is then engaged 35 and its course obstructed and deflected by the first of the depending baffles or partitions 12 under which it passes toward the discharge end of the flume. The water or other fluid is successively engaged by alternate 40 bottom baffles 8 and depending baffles or partitions 12 and is thereby caused to flow through the flume from one end to the other in a tortuous path. Any sludge or heavy solids in the water which become 45 precipitated during the passage of the water through the flume will be caused to pass from one side to the other of the lower series of baffles 8 by the current of water which flows through the openings or 50 passages 10 in the lower edge of the lower series of baffles and will be discharged from the end of the flume.

The depending partitions 12 cause an air 55 pocket to form behind each of these partitions and the flowing stream of water compresses the air in the so formed pockets to a greater or lesser extent, depending upon the velocity of the flowing stream of water, and causes agitation of the water so that 60 the water becomes thoroughly aerated and, in the case of neutralized mine water, to become thoroughly oxidized in passing through the flume. The rapidly flowing stream of water will also induce the flow 65 of air into the flume through the series of

openings 15 provided for that purpose in the sectional cover or top 2^a, and in this way cause the air to become mixed with and further aerate and oxidize the neutralized mine water.

The provision of the successive and alternate top baffles 12 and bottom baffles 8 causes successively different quantities of air to be intimately mixed with the water in passing through the flume, avoids the necessity of using mechanical means for aerating and oxidizing the water and avoids the use of a supply of compressed air to aerate the water.

The advantages of my invention will be appreciated by those skilled in the art. The 80 apparatus is simple and will not require frequent or expensive repairs. The fluid in passing through the flume is agitated by and becomes intimately mixed with air and is aerated, and with an acid fluid is oxidized 85 thereby without the use of mechanical means and without interruption of the flow of the fluid.

Modifications in the construction and arrangement of the parts may be made without departing from my invention. The flume may have a single compartment or a series of compartments, instead of two compartments as is shown in the drawings. The construction and location of the openings in the baffles and in the top or cover 90 of the flume may be varied and other changes may be made without departing from my invention as defined in the appended claims.

I claim:—

1. A flume comprising walls forming a bottom and sides, an inlet at one end to admit a stream of liquid, an outlet at the opposite end to discharge said liquid, the bottom 105 of said flume being inclined downwardly toward the discharge end thereof, a sectional top forming a removable cover, and a series of transverse baffles within the flume with part of said series of baffles extending vertically upward from the bottom and part 110 extending vertically downward from the top to an intermediate point in the height of the flume, and with the upper edge of said upwardly extending baffles in a plane above 115 the plane of the lower edge of the depending baffles.

2. A flume comprising walls forming a bottom and sides, an inlet at one end to admit a stream of liquid, an outlet at the opposite end to discharge said liquid, the bottom 120 of said flume being inclined downwardly toward the discharge end thereof, and a series of transverse baffles within the flume, with part of said series of baffles extending vertically upward from the bottom and part 125 extending vertically downward from the top to an intermediate point in the height of the flume, and with the upper edge of said upwardly extending baffles in a plane 130

- above the plane of the lower edge of the depending baffles, and a series of openings in the upwardly extending baffles adjacent to the bottom of the flume forming passages connecting opposite sides of said baffles. 5
3. A flume comprising walls forming a bottom and sides, a sectional top forming a removable cover, and a series of transverse baffles within the flume, with part of said series of baffles extending vertically upward from the bottom and part extending vertically downward from the top to an intermediate point in the height of the flume, and with the upper edge of said upwardly 10 extending baffles in a plane above the plane of the lower edge of the depending baffles, and a series of openings in the depending baffles adjacent the upper edge thereof forming air passages connecting opposite sides 15 of the baffles. 20
4. A flume comprising walls forming a bottom, sides, and a sectional top forming a removable cover, a series of transverse baffles within the flume with part of said series of baffles extending vertically upward from the bottom and part extending vertically downward from the top to an intermediate point in the height of the flume, and with the upper edge of said upwardly 25 extending baffles in a plane above the plane of the lower edge of the depending baffles, a series of openings in the depending baffles adjacent the upper edge thereof forming air passages connecting opposite sides 30 of the baffles. 35
5. A flume comprising walls forming a bottom, sides, and a sectional top forming 40 a removable cover, a series of transverse baffles within the flume with part of said series of baffles extending vertically upward from the bottom and part extending vertically downward from the top to an intermediate point in the height of the flume, and with the upper edge of said upwardly 45 extending baffles in a plane above the plane of the lower edge of the depending baffles, a series of openings in the upwardly extending baffles adjacent the bottom of the flume connecting opposite sides of the baffles, a series of openings in the depending baffles adjacent the upper edge thereof forming air 50 passages connecting opposite sides of the baffles, and a series of openings in the removable cover adjacent to the depending baffles forming air passages into the flume on the discharge side of said depending baffles. 55
6. A flume comprising walls forming a bottom and sides, an inlet at one end to admit a stream of liquid, an outlet at the opposite end to discharge said liquid, a sectional top forming a removable cover, and a 60 series of transverse baffles within the flume with part of said series of baffles extending vertically upward from the bottom and part extending vertically downward from the top to an intermediate point in the 65 height of the flume, and with the upper edge of said upwardly extending baffles in a plane above the plane of the lower edge of the depending baffles. 70

In testimony whereof I have hereunto set 75 my hand.

ELGIE C. AULD.
